D7448

OF D 14,910

No. 14,910

MARCH 25, 1884

UNITED STATES PATENT OFFICE.

WARREN P. JENNINGS, OF BROOKLYN, NEW YORK.

DESIGN FOR A MITT.

SPECIFICATION forming part of Design No. 14,910, dated March 25, 1884.

Application filed December 19, 1883. Term of patent 7 years.

To all whom it may concern:

Be it known that I, WARREN P. JENNINGS, a resident of Brooklyn, in the county of Kings and State of New York, have invented and produced a new and original Design for Ladies' Mitts, of which the following is a full description, in connection with the accompanying photograph, which represents a face view of my new design for a mitt.

10 This invention relates to a new design for ladies' mitts; and it consists in the arrangement of apertures that form figures for ornamenting the mitt, as hereinafter more fully described.

15 *a b c d* are rows of dots, each row containing a series of dots alternating with blank spaces, the blank spaces in each row being in line with the dots in the next adjoining row, as shown.

20 *e e* are rosettes ranged in rows, with clouds or darker portions *f* between the rosettes in each row.

25 *g* are angular fields formed of small dots.

h i are rows of dots having between them rows *j k l m*, of alternating dots and blank spaces, analogous to the rows *a b c d*.

n o, and *p* are rows of dots, and *r r* are angular fields composed of dots, such fields being located between the rows *n* and *o*.

I claim--

- 30 1. The design for mitts, the same consisting of the figures *c* and cloud-like darker figures *f*, substantially as shown.
2. The design for mitts, the same consisting of the figures *c f*, and *g*, substantially as shown.
- 35 3. The design for mitts, the same consisting of the rows *n o p* and figures *r*, substantially as shown.
4. The design for mitts, the same consisting of the figures *a b c d e f g h i j k l m n o p r*, substantially as shown.

WARREN P. JENNINGS.
